UNITED STATES PATENT OFFICE.

HERBERT E. MARKS, OF SEWICKLEY, PENNSYLVANIA.

ROOF CONSTRUCTION.

Application filed March 25, 1925. Serial No. 18,141.

The invention relates to roof decks and to the construction of slabs for forming them, and the object is to provide a fire-proof roof deck which is effective for its intended purpose, and which is very economical to construct, because, among other reasons, of the simplicity of the slabs of which it is made, the lightness of their weight, and the ease with which they may 10 be laid to form a deck.

The invention is illustrated in the accompanying drawings, of which Fig. 1 is a plan view of a portion of a roof deck; Fig. 2 a detail sectional view to enlarged scale taken 15 on the line II—II, Fig. 1, showing a pair of adjacent slabs as they appear when laid upon supporting members and before the roof is finished; Fig. 3 a view similar to Fig. 2, showing the completion of a joint 20 between the sides of adjacent slabs; Fig. 4 a detail sectional view to enlarged scale taken on the line IV—IV, Fig. 1; Fig. 5 a plan view of portions of adjacent sides of a pair of slabs showing modifications of 25 construction, and Fig. 6 a sectional view taken on the line VI—VI, Fig. 5.

In the practice of this invention a roof deck is formed of a plurality of slabs, each of which is made of a plurality of wooden 30 boards of sufficient thickness in proportion to their span lengths to sustain a required roof load. The load-sustaining portions which enter into the construction of a slab are held in slab-formation by a board of 35 fireproofing material which is firmly attached to the faces of the wooden boards and is sufficiently rigid to tie the boards together and maintain them in the form of a slab. The preferred form of board for 40 this purpose is what is known as a plaster or gypsum board. While a single gypsum board may be used, it is preferred to use two, one attached to the lower, and the other to the upper faces of the wooden 45 boards.

Having reference to the illustrative embodiment of the invention, a roof deck is generally indicated in Fig. 1 as being formed of a plurality of slabs A resting on 50 purlins 1. The slabs may similarly rest upon sub-purlins or upon rafters, the term "purlins" being here used as including both sub-purlins and rafters; and the slabs may, as far as concerns some features of the invention, be otherwise supported.

As shown in Fig. 2 each slab A is formed

of a plurality of wooden boards 2 having rigid boards 3 of fireproofing material attached to their lower faces. The wooden boards preferably have plane-faced sides 60 as shown in Fig. 2, but may be dove-tailed, as indicated at 4 in Fig. 6. As previously explained, rigid boards 5 of fireproofing material are preferably firmly attached to the top faces of boards 2 to assist the lower 65 boards 3 in holding the wooden boards in slab formation, as well as to fireproof the tops of the slabs. The attachment of the lower and upper boards 3 and 5 to the wooden core-forming boards 2 is preferably 70 effected by nailing the former to the latter as shown in Fig. 2, but may be effected by cementing the fireproofing boards to the wooden boards as indicated at 6 in Fig. 6, silica cement preferably being used for this 75 purpose.

In addition to the provision of rigid boards of fireproofing material for performing the double function of holding load-sustaining wooden boards in slab formation and of 80 fireproofing their faces, the invention in its preferred form contemplates the provision of fireproofing material at the edges of the wooden boards at the sides of the slabs. This is preferably done by extending the 85 edges of lower boards 3 beyond the sides of slabs A, as indicated at 7 in Fig. 2, to form a support for cementitious fireproofing material which may be poured upon the projecting ends 7 and between the adjacent sides 90 of the wooden boards after the slabs have been laid in position. Such a filling of fireproofing material, preferably of gypsum, is indicated at 8 in Fig. 3.

It will be understood that unequal loads 95 applied to adjacent slabs may be such as cause sufficient deflection of one slab with relation to the other to break the fireproofing seal 8 between the sides of the slabs, and also to break or injure the waterproofing 100 layer which is customarily applied to the top of the deck. To resist such relative movements between the sides of adjacent slabs, the upper fireproofing boards 5 are preferably set back from the edges of the 105 slabs, and a plate 9 laid between the edges of plates 5 and attached to the upper faces of boards 2, the plate spanning the adjacent edges of the slabs. Plate 9 is preferably formed of rigid fireproofing material the 110 same as plates or boards 3 and 5, and preferably extends the full length of the slabs

as shown in Fig. 1. They may be, and preferably are, nailed to boards 2, as shown in Fig. 3, but may be cemented to them as shown in Fig. 6.

5 Instead of providing a monolithic fill 8 of fireproofing material between the sides of adjacent slabs as shown in Fig. 3, the sides of the slabs may be fireproofed by applying to them bodies 10 of gypsum or other fire-
10 proofing material as indicated in Fig. 6.

When this is done, both top and bottom boards 3^a and 5^a preferably extend beyond the wooden boards 2^a at the sides of the slabs to form pockets for receiving and holding
15 the fireproofing bodies 10. When the slabs are so constructed, top boards 3^a are preferably notched out at their edges at suitable intervals as indicated at 11 in Fig. 5, and plates 12 placed in the notches and attached
20 to the upper faces of boards 2 to resist relative vertical movement between the adjacent sides of the slabs.

As shown particularly in Fig. 4, the ends of the slabs preferably rest upon the upper
25 flanges of purlins 1. To hold them in position their bottom faces may be provided with suitable attaching members, such as screw
clips 15, constructed to engage the flanges of the purlins. For tying the slabs together
30 at their ends, top plates 5 are preferably set back from the ends, and a joint-spanning
plate 16 laid between their ends and nailed or otherwise attached to the upper faces of
boards 2.

35 Assuming, by way of example and not of limitation, that roof purlins are spaced at six foot intervals, a slab may be formed of wooden boards about eight inches wide, one and a half inches thick and about six
40 feet long. The space between adjacent sides of the slabs for receiving fireproofing material may be about one inch wide. The slabs may be made at a factory and shipped to the site of erection, or may be made at the
45 site. In either case they may be formed at a minimum cost. They are light in weight, and accordingly may be easily raised to a roof and easily manipulated to lay them upon supporting members. If the sides of
50 the slabs are provided with a fireproofing material after the slabs have been laid in position, this may be quickly and economically done by workmen standing upon the slabs. Thereafter, the sides of the slabs are
55 tied together by plates 9 or 12, and their ends by plates 16. After the deck is completed it may be covered by any desired form of weather-proofing or other protecting material.

60 Not only is there manifest economy in the construction of the slabs and in laying a roof with them, but an indirect economy arises from their lightness in weight, because the supporting structure may be correspondingly
65 light.

According to the provisions of the patent statutes, I have explained the principle and operation of my invention, and have illustrated and described what I now consider to represent its best embodiments. However,
70 I desire to have it understood that, within the scope of the appended claims, the invention may be practiced by other forms of construction than that particularly shown and described.

75 I claim as my invention:

1. In a roof, the combination with spaced purlins, of a roof deck comprising a plurality of preformed slabs resting at their ends upon said purlins, each slab being formed of a plurality of load-sustaining wooden boards having firmly attached to their lower faces rigid boards of fireproofing material holding the boards in slab formation, said boards of fireproofing material projecting beyond the sides of the slabs, and cementitious fireproofing material at the sides of the slabs supported by said projecting portions of said fireproofing boards.

80 2. In a roof, the combination with spaced purlins, of a roof deck comprising a plurality of preformed slabs resting at their ends upon said purlins, each slab comprising a plurality of load-sustaining wooden boards having firmly attached to their lower faces a rigid board of fireproofing material holding the wooden boards in slab formation, said boards of fireproofing material projecting beyond the sides of the slabs, cementitious fireproofing material laid at
85 the sides of the slabs upon said projecting portions of the fireproofing boards, and a rigid plate spanning the adjacent sides of slabs and attached to their faces for resisting relative vertical movements of said slabs
90 at their adjacent sides.

95 3. In a roof, the combination with spaced purlins, of a roof deck comprising a plurality of preformed slabs resting at their ends upon said purlins, each slab being formed of a plurality of load-sustaining wooden boards having rigid boards of fireproofing material firmly attached to their upper and lower faces holding the wooden boards in slab formation for handling, said fireproofing boards on the lower faces of the slabs projecting beyond the sides of the slabs, monolithic fills of cementitious fireproofing material between the sides of said slabs supported by said projecting portions of said fireproofing boards, and rigid plates spanning the adjacent side of slabs and attached to their faces for resisting relative vertical movements of the slabs at their adjacent sides.

100 4. In a roof, the combination with spaced purlins, of a roof deck comprising a plurality of preformed slabs resting at their ends upon said purlins, each slab comprising a core formed of a plurality of load-sus-

taining wooden boards having rigid boards of fireproofing material firmly attached to their upper and lower faces holding the wooden boards in slab formation prior to

5 the laying of the slabs, said fireproofing boards on the lower faces of the slabs projecting beyond both sides of each slab, a monolithic fill of fireproofing cementitious material between the sides of adjacent slabs

10 and supported by said projecting portions of fireproofing boards, said fireproofing boards on the upper faces of the slabs being set back from both sides of each slab, and rigid plates spanning the adjacent sides of

15 slabs and attached to their upper faces for resisting relative vertical movements of the slabs at their adjacent sides.

5. In a roof, the combination with spaced purlins, of a roof deck comprising a plurality of preformed slabs resting at their ends upon said purlins, each slab comprising a core formed of a plurality of load-sustaining wooden boards having rigid gypsum boards firmly attached to their upper and 20 lower faces holding the wooden boards in slab formation prior to the laying of the slab, said gypsum boards on the lower faces of the slabs projecting beyond both sides of each slab, monolithic fills of fireproofing 25 cementitious material between the sides of adjacent slabs and supported by said projecting portions of fireproofing boards, said gypsum boards on the upper faces of the slabs being set back from both sides of each slab, and rigid gypsum boards spanning the 30 adjacent sides of slabs and attached to their upper faces for resisting relative vertical movements of the slabs at their adjacent sides, said fireproofing 35 boards on the upper faces of the slabs being set back from the ends of the wooden boards, and rigid plates spanning the adjacent ends of slabs and attached to their upper faces between the ends of said upper

adjacent sides of slabs and attached to their upper faces for resisting relative vertical movements of the slabs at their adjacent sides.

6. A roof deck comprising spaced purlins, 40 and a plurality of preformed slabs resting at their ends upon said purlins, each slab comprising a core formed of a plurality of load-sustaining wooden boards having rigid boards of fireproofing material attached to 45 their upper and lower faces holding the wooden boards in slab formation prior to the laying of the slab, said fireproofing boards on the lower faces of the slabs projecting beyond both sides of each slab, 50 monolithic fills of fireproofing cementitious material between the sides of adjacent slabs and supported by said projecting portions of fireproofing boards, said fireproofing 55 boards on the upper faces of the slabs being set back from both sides of each slab, rigid plates spanning the adjacent sides of slabs and attached to their upper faces for resisting relative vertical movements of the slabs at their adjacent sides, said fireproofing 60 boards on the upper faces of the slabs being set back from the ends of the wooden boards, and rigid plates spanning the adjacent ends of slabs and attached to their upper faces between the ends of said upper 65 fireproofing boards and tying the ends of the slabs together.

In testimony whereof, I sign my name.

HERBERT E. MARKS.
